UNITED STATES PATENT OFFICE.

THOMAS DEWIT STARK, OF REDBLUFF, CALIFORNIA.

PUMP-LIFTER.

SPECIFICATION forming part of Letters Patent No. 722,463, dated March 10, 1903.

Application filed April 24, 1902. Serial No. 104,422. (No model.)

To all whom it may concern:

Be it known that I, THOMAS DEWIT STARK, a citizen of the United States, residing at Redbluff, in the county of Tehama and State of California, have invented certain new and useful Improvements in Pump-Lifters, of which the following is a full and complete specification, such as will enable those skilled in the art to which it appertains to make and use the same.

The object of this invention is to provide an improved apparatus for removing pumps from deep wells, a further object being to provide an apparatus of this class which is simple in construction and which may be conveniently operated to accomplish the desired result without danger of the pump-pipe and its attachments dropping back into the well, and thus occasion great inconvenience, delay, and danger of breakage, and consequent damage.

The invention is fully disclosed in the following specification, of which the accompanying drawings form a part, in which the separate parts of my improvement are designated by the same reference characters in each of the views, and in which—

Figure 1 is a plan view of my improved pump-lifting apparatus; Fig. 2, a side elevation thereof; Fig. 3, a central longitudinal section, and Fig. 4 a rear end view thereof.

In the practice of my invention I provide an apparatus for the purpose specified which comprises an oblong frame composed of two side members a , connected at their rear ends by a transverse block a^2 , and to the front end of which is hinged, at one side, as shown at a^3 , a head-block h^4 , which is also connected with the opposite side of the frame at a^5 in the same manner as at a^3 . The connections of the headed block a^4 with the main frame at a^3 and a^5 is made by means of jaws through which are passed a pivot-pin, and by removing either of the pivot-pins at a^3 or a^5 the headed block a^4 may be swung on its opposite connection, as will be readily understood.

Between the side members a of the main frame and forwardly of the transverse rear block a^2 is placed a block b , which is movable longitudinally of the main frame, and passing through the block a^2 is a screw b^2 , which bears on the block b and is intended to force

the same forwardly when desired; but this screw may, if preferred, have a bearing in said block b by which the latter may be moved both forwardly and backwardly. Hinged to the front side of the block b , as shown at b^3 , is a jaw b^4 , the front end of which is provided with a circular recess having teeth b^5 , and secured in the central rear portion of the head a^4 is a stationary jaw a^6 , having corresponding teeth a^7 . The jaw b^4 is provided on its top side with two parallel raised portions b^8 , which may be formed integrally therewith or be formed separately and be secured thereto, and passed through the front and rear ends of these raised portions b^8 are rods b^9 and b^{10} . To the rod b^9 , which is near the front end of the jaw b , is pivoted a lever c , the rear end of which passes beneath the rod b^8 and the front end of which projects forwardly and is connected with the base member c^2 , secured to the head a^4 by any suitable flexible connections c^3 , such as a rope, chain, strap, or similar device. Pivoted or hinged at the opposite side of the main frame, as shown at d , is a support d^2 , and in the top of this support is pivoted at d^3 a lever d^4 , to the shorter arm of which is pivoted, as shown at d^5 , a link d^6 , to which is pivoted a swinging jaw e , having a downwardly-directed member e^2 , which is adapted to bear under certain conditions against the rod b^8 , and the end of the longer arm of this jaw projects forwardly and is provided with a segmental recess e^3 , provided with teeth e^4 , and pivoted to said arm of said jaw is a yoke-shaped jaw e^5 , and the front end of the longer arm of the jaw e is provided with lateral flanges e^6 , which overlap the sides of the yoke-shaped jaw e^5 .

In Figs. 1, 2, and 3 I have shown at f the pipe of a pump, and the operation of this apparatus will be readily understood from the foregoing description when taken in connection with the accompanying drawings and the following statement thereof. The main frame is preferably provided with longitudinal bottom supports g , which are adapted to rest on suitable tracks or ways, whereby the apparatus may be conveniently moved forwardly and backwardly, and in practice one of the pivotal connections of the head a^4 is broken by removing the corresponding pivot-pin, and said head is swung around and the apparatus

is moved forwardly until the pipe f comes in contact with the front end of the jaw b^4 . The head a^4 is then swung back into position, as shown in Figs. 1, 2, and 3, and the connection 5 with the main frame is firmly made. The parts are shown in operative position in Figs. 2 and 3, and after the operation before described the lever d^4 and swinging jaw e are manipulated so as to pass the pipe f upwardly 10 through the yoke-shaped jaw e^5 , and in order to raise the pipe f all that is necessary is to depress the longer arm of the lever d^4 . In this operation the pipe f will be raised a certain distance each time that the lever d^4 is 15 depressed, and when said lever is released or the pressure thereof is removed the shorter arm thereof will descend and the jaws e and e^5 will automatically descend on the pipe f , and will thus be enabled to successively grasp 20 said pipe at a lower point at each successive movement of the lever d^4 . At this operation the jaw b^4 moves upwardly at each upward movement of the pipe, and said pipe is free to move vertically between the jaws a^6 and b^4 , 25 and in the operation of lowering the jaw e , as before described, the jaws b^4 and a^6 grasp and hold the pipe and prevent its return into the well. The lever c is intended to provide means for raising said jaw so as to permit of 30 a coupling or coupling-head of the pipe f passing upwardly through the frame, and the flexible connections c^3 of said lever is intended to prevent too great a vertical movement thereon. The downwardly-directed member 35 e^2 of the jaw e is intended to hold said jaw and its attachments in proper relative position when the lever d^4 is in the position shown in Fig. 3; but this member e^2 of the jaw e is not an absolute necessity and may or may 40 not be employed, and it will be understood that whenever the lever d^4 is depressed, as hereinbefore described, the connection of said member with the rod b^8 is broken and the said jaw is raised above the main frame. 45 This apparatus may also be employed in connection with an ordinary derrick, in which case the lifting apparatus of the derrick would be connected with the jaw e at d^7 instead of the link b^6 , which forms a connection with 50 the lever d^4 , and in this event the operation will be substantially the same as that hereinbefore described when the lever d^4 is employed.

It will be understood that this apparatus 55 may be adapted for use in connection with pump devices of any size by simply and properly adjusting the position of the block b , which is done by means of the screw b^2 , and the movement of said block forwardly in the 60 operation of the apparatus is also prevented by the pipe f of the pump.

By means of this apparatus a pump-pipe of any length may be quickly and easily re-

moved from a well without danger of accident of any kind, and this apparatus may be 65 manipulated by two people or by a man and a boy, and by means thereof a great saving of time and expense is accomplished and the danger of accidents which frequently occur in operations of this class is avoided. 70

The downwardly-directed member e^2 of the jaw e is not an absolutely essential feature, and the position of this member will always depend upon the position of said jaw, and instead of using the jaw b^4 in connection with 75 block b another form of sliding block may be provided which will operate directly in connection with the head a^4 or the jaw a^6 , which is connected therewith, and the jaw b^4 may also be provided with a supplemental head, 80 with which the teeth b^5 will be connected, and this jaw or this head may be straight or concave, as desired.

Having fully described my invention, what I claim as new, and desire to secure by Letters 85 Patent, is—

1. In an apparatus of the class described, a frame provided at the front end with a hinged member, the center portion of which is provided with a clamping-jaw having backwardly-directed teeth, a slideable block mounted in said frame and provided with a forwardly-directed jaw having corresponding teeth, a support pivoted to said frame or hinged thereto, a lever connected with said support, a swinging jaw suspended from said lever and a yoke-shaped jaw pivotally connected with said swinging jaw, the jaw which is connected with said slideable block being also provided with a lever which projects forwardly and is adapted to be connected with the main frame, substantially as shown and described. 90

2. In an apparatus of the class described, a main frame, a head hinged to the front end thereof and provided centrally with a backwardly-directed jaw, a slideable block mounted in said main frame and provided with a pivoted forwardly-directed jaw, a lever connected with said pivoted jaw and projecting forwardly and adapted to be connected with the main frame, a swinging jaw suspended above the main frame and provided with a yoke-shaped jaw which is pivotally connected therewith and means for moving said slideable block forwardly, substantially as shown and described. 95

In testimony that I claim the foregoing as my invention I have signed my name, in presence of the subscribing witnesses, this 15th day of April, 1902.

THOMAS DEWIT STARK.
